US00D523335S

(12) **United States Design Patent** (10) **Patent No.:** **US D523,335 S**
(45) **Date of Patent:** **** Jun. 20, 2006**

(54) **APPLICATOR FOR FLUID DISPENSER**

(75) Inventors: **Joel L. Nelson**, Agoura Hills, CA (US);
Jeffrey J. Hager, Camarillo, CA (US);
Laura A. Nelson, Agoura Hills, CA (US)

(73) Assignee: **Spatz Laboratories**, Oxnard, CA (US)

(**) Term: **14 Years**

(21) Appl. No.: **29/202,702**

(22) Filed: **Apr. 1, 2004**

(51) **LOC (8) Cl.** **09-07**

(52) **U.S. Cl.** **D9/447**

(58) **Field of Classification Search** D9/726,

(57) **CLAIM**

The ornamental design for an applicator for fluid dispenser, as shown and described.

DESCRIPTION

FIG. 1 is a left side isometric view of an applicator for fluid dispenser showing our new design;

FIG. 2 is a front elevational view thereof, the back elevational view being identical thereto;

FIG. 3 is a right side elevational view thereof, the left side being identical thereto;

FIG. 4 is a top plan view thereof; and,

FIG. 5 is a bottom plan view thereof.
